SIFTER TOP FOR GRANULAR MATERIAL CONTAINERS, WITH DISPENSING CLOSURE THEREFOR, REMOVABLY ATTACHABLE IN TWO DISPENSING POSITIONS

Ralph K. Pottle, New York, N. Y., assignor to American Can Company, New York, N. Y., a corporation of New Jersey

Application October 23, 1946, Serial No. 705,218

4 Claims. (Cl. 222—480)

1

The present invention relates to sifter top containers suitable for pulverulent or granular material and has particular reference to a container having a slide member which may be readily snapped on or removed from the container.

An object of the invention is the provision of a sifter top container having a detachable slide member of simple and economical construction which is retained in place on the container by simple projections of the end seam, such simplified construction resulting in easier manufacture and assembly of the parts while simultaneously reducing the cost of production.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a container embodying the instant invention;

Fig. 2 is an exploded perspective view showing parts of the container in separated and superimposed position; and

Figs. 3 and 4 are enlarged sectional views taken substantially along respective vertical planes indicated by the lines 3—3, 4—4 in Fig. 1, with parts broken away.

As a preferred embodiment of the invention the drawing illustrates a sheet metal sifter top container made preferably of tin plate or the like material and adapted to hold granular products such as spices, etc. The container includes a tubular body 11 of rectangular cross section having rectangular top and bottom end members 12, 13 secured thereto in suitable end seams 14. The bottom end member 13 preferably is imperforate.

The top end member 12 preferably is of the countersunk panel type and is formed with a countersunk bottom wall 16 having an integral surrounding upright wall section 17 which fits snugly within the top end of the body 11. The upper edge of the upright wall section 17 merges into a flange 18 (Fig. 3) which preferably is interfolded with a similar flange on the body to produce the upper end seam 14 mentioned above.

The bottom wall 16 of the top end member 12 is formed with an elongated, generally rectangular shaped dispensing opening 21 through which the contents of the container may be removed with a spoon or other tool in bulk form. Such an opening is arranged longitudinally off center for a purpose hereinafter explained. This opening is normally covered with a sifter slide member 23 which is disposed in the countersunk panel of the top end member.

2

The sifter slide member 23 preferably is rectangular in shape and is flat and rests or engages against the outer or upper surface of the bottom wall 16 of the top end member 12. The outer or peripheral edge of the slide member is formed with an upwardly and outwardly bent curl which terminates in the plane of the bottom surface of the slide member and thus provides a smooth curled edge 24.

The slide member is provided with a plurality of sifter holes or perforations 25. These are shown as being arranged in single rows adjacent both ends although if desired only one row of holes located at one end will suffice. There is this advantage in having a row of openings at either end, when so constructed the slide member may be put back onto the container with either end over the off-center dispensing opening 21. As illustrated in Fig. 3 only the row 20 of sifter holes 25 on the slide member which is over the lesser width of countersunk panel bottom wall 16 at the end of the opening 21 is effective for dispensing the contents. In other words, when the slide member is in the position 15 of Fig. 3, that is to the right, both rows of perforations 25 are blocked off by the wall 16. However, if the slide is moved to the left the right hand row of perforations will align with the dispensing opening 21 of the end member and sifting 25 may be had. It will now be evident why the dispensing opening 21 is off-center.

In width, the slide member 23 is substantially the same size as the countersunk panel of the end member 12, the curled edge 24 along the two 35 longitudinal sides of the slide member slidably engaging the adjacent inner surfaces of the upright wall section 17 of the end member. The upright wall section 17 thus serves as a guide for the slide member. In length, the slide member 40 is slightly shorter than the inner longitudinal dimension of the countersunk panel to permit sliding of the perforations 25 into and out of sifting alignment with the dispensing opening 21 in the end member 12. Corrugations 26 formed 45 in the slide member are provided for manually sliding the member into and out of sifter position.

The slide member 23 is retained in operative 50 position against the bottom wall 16 of the end member 12 by a plurality of small nodular projections 27 which extend inwardly from the end seam 14. There are two of these projections 27 along each of the two longitudinal sides of the container. These projections are produced by 55 forming shallow indentations 28 (see Fig. 4) in the upper, outer edge of the seam 14, the result being a forcing of a portion of the seam inwardly into a position overlying and in vertically spaced relation to the bottom wall 16 of the end member 12. The resulting projection 27 extends in-

wardly just enough to lightly engage the curled edge 24 of the slide member and to retain the slide member in place with a snap-on fit.

With such a construction of sifter top container the projections 27 permit of easy sliding of the slide member 23 along the end member to bring the sifter perforations into alignment with the dispensing opening for a sifter operation or to entirely close off the dispensing opening when desired. The projections 27 also permit of easy removal of the slide member 23 from the container so that free access may be had to the dispensing opening for removing the contents in bulk form.

This removal of the slide member may be readily effected by prying the member off with a knife, spoon, or other tool applied to one end of the members. The slide member may be just as easily replaced, by a mere snapping of the curled edge 24 under the projections 27. This ease of applying and removing the slide member from the container greatly facilitates manufacturing and assembling operations and thus is conducive to economy in production.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sifter top container, comprising in combination a body, an end member having a flat countersunk bottom wall secured to said body in an upstanding seam, said end member having a central dispensing opening therein through which the contents of the container may be removed in bulk form, inwardly extending projections on said seam on two oppositely disposed sides of the container and in spaced relation to the bottom wall of said end member, and a snap-on member having sifter holes therein located off center and having a curled edge completely surrounding the periphery of the snap-on member and engageable under said seam projections for holding the same against the flat bottom wall of said end member for covering its dispensing opening, said snap-on member being slideable along said end member for aligning its off center holes with said centrally disposed dispensing opening for sifting the contents from the container and being removable bodily from under said seam projections for exposing said central dispensing opening for bulk dispensing of the container contents from said dispensing opening.

2. A sifter top container, comprising in combination a body, a rectangular end member having a flat countersunk bottom wall secured to said body in a surrounding upstanding seam, said end member having a dispensing opening extending longitudinally in its flat bottom wall through which the contents of the container may be removed in bulk form, inwardly extending projections on said seam on oppositely disposed sides of the container and in spaced relation above the flat wall of said end member, and a rectangular snap-on member of shorter length than the distance between the opposed seam sections at the ends of said end member, said snap-on member having sifter holes therein and being insertable under said seam projections and extending into engagement with the opposed

seam sections at the sides of said end member, said inserted snap-on member engaging the flat wall of said end member for covering its dispensing openings, said snap-on member being slideable along said end member for aligning said holes with an end of said dispensing opening for sifting the contents from the container and being bodily removable from under said seam projections for exposing said dispensing opening for bulk dispensing of the container contents.

3. A sifter top container comprising in combination a body, a rectangular end member secured to said body in a surrounding upstanding seam, said end member having a dispensing opening therein located longitudinally off center through which the contents of the container may be removed in bulk form, inwardly extending projections on said seam on oppositely disposed long sides of the container and at spaced relation to said end member, and a rectangular snap-on member having sifter holes therein disposed in a row extending along each short end of the member, said snap-on member being insertable under said seam projections in either of two positions for engaging said end member and covering its dispensing opening, said snap-on member being slideable longitudinally of the end member for aligning one row of said sifter holes with said dispensing opening for sifting the contents from the container and also being removable from under said seam projections for bulk dispensing of the container contents from said dispensing opening said snap-on member being replaceable in the alternate position to render the other row of sifter holes effective for dispensing purposes.

4. A sifter top container, comprising in combination a rectangular body, a rectangular end member secured to said body in an upstanding seam, said end member having a countersunk bottom wall with a rectangular dispensing opening one end edge of the opening being nearer the adjacent part of the upstanding seam than the other end edge to its seam part leaving an adjoining narrow wall section of the said bottom wall at that end of the opening, said seam along oppositely disposed sides having projections overlying and spaced above the bottom wall of said end member, and a rectangular snap-on member having a straight row of sifter holes at each end and being insertable under said seam projections with either row of holes over the narrow bottom wall section of said end member, said snap-on member being slideable longitudinally for aligning the row of holes over the narrow end wall section with said dispensing opening for sifting the contents from the container, said snap-on member also being removable from under said seam projections for bulk dispensing of the container contents from said dispensing opening.
